AIR CONDITIONING UNIT AND APPARATUS
FOR SHIPPINGBernard W. Jewell, Wichita, Kans., assignor to
The O. A. Sutton Corporation, Inc., Wichita,
Kans., a corporation of Kansas

Application August 1, 1952, Serial No. 302,265

4 Claims. (Cl. 206—46)

1

My present invention relates to means for restraining a heavy portion of a heavy appliance during shipment thereof, the invention being of particular utility in the shipment of window ledge air conditioning units. In appliances of this character there may be a heavy, motorized unit, such as the hermetically sealed motor-compressor unit commonly found in window ledge air conditioning units. The motor-compressor unit must be resiliently supported and otherwise isolated from the body of the appliance so as to eliminate or minimize the transmission of noises and vibrations therefrom to the casing of the unit when the appliance is in operation. On the other hand, the motorized portion of such an appliance must be firmly held in position during shipment of the unit or severe damage and possible destruction of the unit will result. Heretofore it has been the practice to provide special holding means, such as clamps, shipping bolts and other threaded fastening members, firmly to unite the motorized portion to the body of the unit during shipment. Such means are usually difficult of access and usually require the installer to remove access plates or a portion of the casing of the unit in order to remove or loosen the shipping hold-down means. A primary object of the present invention is to eliminate such expensive, and difficult to operate, temporary holding means.

A further object of the present invention is to provide a shipping pallet for an air conditioning unit or equivalent appliance, which pallet is firmly attached to a portion of the unit during shipment, the unit and the pallet being cooperatively related to provide means for restraining the motorized portion of the unit, such as the hermetically sealed compressor thereof, against movement during shipment, and the unit being so arranged that it is ready for immediate operation when the shipping pallet is separated therefrom.

Another object of the present invention is to reduce the ultimate cost of appliances of the character described by providing means for safe transit of the unit, and which means is of economical construction.

The objects and advantages of the present invention will be more readily understood from inspection of the accompanying drawings taken in connection with the following specification, and wherein the present invention is illustrated in the combination of an air conditioning unit and its shipping container.

In the drawings,

Fig. 1 is a partially schematic representation of an air conditioning unit, having the present in-

2

vention associated therewith and illustrated in complete detail;

Fig. 2 is a plan view, on an enlarged scale, of a portion of the floor of the unit illustrated in Fig. 1 and associated portions of a shipping pallet constructed in accordance with the present invention; and

Fig. 3 is a detail, on an enlarged scale, taken substantially along line 3—3 of Fig. 2.

An appliance comprising a window ledge air conditioning unit is illustrated in Fig. 1, the appliance comprising a housing 10 including a bottom wall 11. The housing is subdivided by a vertical partition 12 into a condenser compartment 13 and an evaporator compartment 14. A hermetically sealed motor-compressor unit 15 is mounted in the condensing compartment, the unit 15 being connected in refrigerant flow relationship with a condenser 16 closing one end of the condenser compartment and an evaporator 17 mounted in the evaporator compartment. The evaporator compartment is divided by a horizontal partition 18 on which is mounted blower means 19 for withdrawing air from the room to be cooled through a room air inlet opening 20 and forcing the same through the evaporator 17 and into the room through the room air outlet opening 21. A condenser blower 22 is mounted in the condenser compartment and driven by a motor 23, there being appropriate shroud means (not shown) whereby air may be caused to enter a portion of the condenser from the outside space, flow in cooling relationship to the motor-compressor unit 15, and be ejected back into the outside space through another portion of the condenser 16. Refrigerant compressed by the motor-compressor unit is forced through a discharge tube 24 into the condenser 16 where it is cooled and liquified. The hot liquid refrigerant travels through a liquid line 25, an expanding member such as expansion valve 26 and supply tube 27 to the evaporator 17 in which it expands to cool the air being forced therethrough by the blower 19. The expanded refrigerant returns to the motor-compressor unit 15 through suction tube 28. The discharge line 24 and suction tube 28 are provided with vibration dampening means such as the large loops illustrated, whereby the motor-compressor unit 15 may vibrate to a large extent without transmitting such vibrations to the casing or other parts of the appliance. Moisture which is condensed from the air to be cooled is collected in a condensate pan 29 beneath the evaporator 17 and is transmitted by gravity through a run-off tube 30 to a pan 31 in which

the lower portion of the condenser 16 is located, whereby the condensate is evaporated and discharged into the outside air. An air conditioning appliance as so far described is conventional, and many details thereof are not illustrated as being within the knowledge of those skilled in the art.

In accordance with the present invention the motor-compressor unit 15 is supported upon a plurality of resilient feet as illustrated in detail in Fig. 3. The resilient feet and associated means comprise a plurality of radially extending arms 35 which are welded to and project outwardly from the bottom of the motorized unit. Each of the arms 35 is provided with a central opening 36 at its outer end in which is positioned a rubber grommet 37 having a large flange at its upper end. A fiber washer 38 rests upon the grommet 37 and engages the head 39 of a bolt 40 extending through the grommet 37 into adjustable engagement with an internally threaded nipple 41 welded into a central opening 42 in a raised boss 43 on the wall 11 of the appliance. A fiber washer 44 surrounds the nipple 41 and supports the lower end of a resilient coil spring 45, the upper end of which engages a fiber washer 46 bearing against the lower surface of the arm 35 and surrounding the grommet 37. A section of rubber tubing 47 surrounds the nipple 41 within the convolutions of the spring 45. The motor-compressor unit 15 is thus supported on a plurality of resilient coil springs 45 which permit vibration and oscillation thereof during operation, while the bolt 40 prevents the motor-compressor unit from extreme movement. The bolt 40 is initially tightened to impart an initial stress to the springs 45 so that the vibration thereof is somewhat limited. All metal parts of the foot assembly are insulated from each other by rubber or fiber members so that rattling and noise transmission are minimized.

During shipment the unit is mounted upon a pallet preferably formed of boards including lowermost, longitudinal boards 50 and uppermost, lateral boards 51, 52, 53, 54, and 55. A plurality of small openings 56 are provided in the wall 11, and a plurality of internally threaded nut members 57 are welded to the wall 11 in surrounding relation to the openings 56. The openings 56 are in such relation to the boards of the pallet that shipping bolts 58 may be passed through holes drilled in the lateral boards, such as boards 52 and 54, into engagement with the holding nuts 57 whereby to draw the pallet into firm, face-to-face engagement with the outer surface of the bottom 11. A bottomless carton may be associated with the pallet during shipment, as illustrated and claimed in detail in my copending application, such a carton being indicated in skeleton outline at 59. The carton protects the exterior of the appliance during shipment, but it is separated from the pallet, and the shipping bolts 58 removed, when the appliance is to be installed.

In accordance with my invention I provide an opening 60 through the wall 11 in central relation to the holding nipples 41, and in vertical alignment with the bottom of the motor-compressor unit 15. The opening 60 is of any suitable configuration and of considerable extent whereby a large block 61 of wood or equivalent material may project therethrough into engagement with the bottom of the motor-compressor unit, the block being attached to the transverse board 53 of the pallet by suitable means such as nails 62. The block is of such height with re-

spect to the resilient feet and associated members that the weight of the unit is lifted from the springs 45 and the flange of the gasket 37 is compressed between the arm 35 and the washer 38 when the bolts 58 are drawn tight. The motor-compressor unit is thereby held in firm association with the shipping pallet and damage of the unit is thus prevented during shipment. When the unit is to be installed the shipping bolts 58 are removed, whereupon the weight of the motor-compressor unit 15 is transmitted to the springs 45 and the appliance is immediately in condition for operating. It is to be noted that no special tools or holding fixtures are required. Ease of installation is thus assured, and service complaints heretofore occasioned by the installation mechanic's forgetting to remove holding clamps or equivalent means are eliminated.

The opening 60, being beneath the motor-compressor unit 15, will provide a further source of cooling air for the condenser 16. In some appliances it may be the only inlet opening for such cooling air, hence eliminating the need for shrouds or the like for directing the air through the machinery compartment. The air which enters the opening 60 enters at a place where it will flow around the shell of the motor-compressor unit. Animals or birds may be prevented from entering the unit by providing an inwardly projecting flange of sponge rubber 63 surrounding the opening 60, which flange projects upwardly into engagement with, or in close relation to, the bottom of the motor-compressor unit when it has settled onto the springs 45.

Having illustrated and described a preferred embodiment of the present invention, it should be apparent to those skilled in the art that the same permits of modification in arrangement and detail. I claim as my invention all such modifications as come within the true spirit and scope of the appended claims.

I claim:

1. In combination for shipping purposes; a heavy appliance including a resiliently mounted, motorized unit, said appliance comprising a bottom wall having an opening therein, means attaching said unit to said wall including a plurality of resilient mounting means in surrounding relation to said opening and resiliently supporting said motorized unit above said bottom wall during operation, and a plurality of threaded members attached to said bottom wall in spaced relation to said opening; a pallet comprising a support projecting through said opening into engagement with the bottom of said motorized unit; and a plurality of shipping bolts engaging said threaded members to hold said pallet and said bottom wall in face-to-face engagement during shipping.

2. In combination for shipping purposes; a heavy appliance including a resiliently mounted, motorized unit, said appliance having a bottom wall, said bottom wall having an opening therein, a plurality of coil springs in spaced, surrounding relation to said opening and resiliently supporting said motorized unit above said bottom wall during operation thereof, limiting means associated with said coil springs for limiting separation of said motorized unit from said bottom wall, and a plurality of threaded members attached to said bottom wall in spaced relation to said opening; a pallet comprising a supporting block projecting through said opening into engagement with the bottom of said motorized unit; and a plurality of threaded shipping bolts

engaging said threaded members to hold said pallet and said bottom wall in face-to-face engagement during shipping, said block being of such height with respect to said movement limiting means that tightening of said shipping bolts firmly to engage said bottom wall with said pallet causes said block to separate said motorized unit from said wall to the extent permitted by said limiting means.

3. The combination during shipment of an air conditioning appliance comprising a motor-compressor unit, a plurality of supporting arms fixed to said unit and projecting laterally therefrom, said appliance having a bottom wall, a plurality of coil springs, each interposed between one of said arms and said bottom wall resiliently to support said motor-compressor unit during operation thereof, a plurality of limiting members each associated with one of said arms for limiting separation of said motor-compressor unit in a vertical direction with respect to said bottom wall, said bottom wall having an opening therethrough beneath said motor-compressor unit, and a plurality of shipping nut members fixed to said bottom wall; with a shipping pallet, said pallet including a block projecting therefrom in such location as to be projectable through said opening into engagement with the bottom of said motor-compressor unit and of such height as to

lift the motor-compressor unit to the extent permitted by said limiting members, and a plurality of bolts engaging said shipping nut members and fastening said bottom wall in face-to-face engagement with said pallet during shipment.

4. An air conditioning appliance comprising a cabinet including a bottom wall, a compressor-condenser-evaporator refrigerating system in said appliance and including a compressing unit, means resiliently supporting said compressing unit during operation thereof, said bottom wall having a large opening therein beneath said compressing unit for reception of a projecting portion of a pallet as an aid to shipment of said appliance, and a continuous rim of sponge rubber surrounding said opening and projecting upwardly therefrom into proximity with the bottom of said compressing unit.
